UNITED STATES PATENT OFFICE

2,378,771

GAS TURBINE NOZZLE

Alan Howard, Schenectady, N. Y., assignor to General Electric Company, a corporation of New York

Application April 26, 1944, Serial No. 532,784

5 Claims. (Cl. 253—78)

In connection with the design of gas turbines, the tendency is to utilize higher and higher temperatures. Temperatures of the order of 1500° F. are now commonly utilized and much higher temperatures are contemplated. The gases are generated by burning fuel and compressed air in a combustion chamber or a plurality of combustion chambers. From the combustion chambers or chambers, the gases are supplied to an annular nozzle box from which they flow through the nozzle passages to the turbine wheel or wheels. The nozzle passages are formed from two relatively heavy rings between which are nozzle partitions which define the contour of the passages; the nozzle partitions are rigidly attached to the two rings in any suitable manner, for example, by welding or by being initially cast integral therewith. Such nozzle partitions are curved, have rounded, relatively thick admission ends or entrance portions and taper to provide relatively thin discharge ends or exit portions.

In the operation of a gas turbine, a uniform temperature does not obtain radially across the nozzle partitions, the partitions being hottest at their radially central portions and cooler at their radially outer and inner ends. This condition obtains due to one or more of several causes. Radiation of heat from the nozzle partitions is more rapid at their ends than at their central portions, and this condition may be magnified when special cooling means are provided for the nozzle partitions; an even temperature may not obtain throughout a combustion chamber with the result that the gases flowing from it to the nozzle box and thence through the nozzle passages may be more or less stratified as to temperature; changes in load may effect changes in temperature of the gases with a resulting non-uniform change in temperature of the nozzle partitions; and in starting up and stopping unequal heating and cooling of the nozzle partitions may result. This unequal heating of the nozzle partitions has a tendency to cause the partitions to become warped at their thin exit edges. In some designs, this is because the edges are elongated permanently while hot which may tend to tear them. Then, when the nozzle partitions cool off, the long thin exit edges are pushed into an irregular bow during contraction. In other designs, the edges may be shortened while hot and there may be a tendency to tear the edge on cooling. In instances, the expansion due to unequal temperature distribution has caused a pull on such edges sufficient to cause them to crack.

The object of my invention is to provide an improved construction and arrangement for overcoming the above difficulty, and for a consideration of what I believe to be novel and my invention, attention is directed to the following specification and to the claims appended thereto.

In the drawing, Fig. 1 is a side view of a portion of a gas turbine embodying my invention; Fig. 2 is a detail sectional view on a larger scale taken on line 2—2, Fig. 1, and Fig. 3 is a detail sectional view taken on line 3—3, Fig. 2.

Referring to the drawing, 1 indicates the nozzle box of a gas turbine to which gases are supplied through a conduit 2, and 3 indicates the turbine wheel carried on a shaft 4 and provided with a ring of buckets 5. Gases are directed from the nozzle box to the turbine wheel by a nozzle ring comprising outer and inner annular rings 6 and 7 between which are located the 10 curved nozzle partitions 8 which define the nozzle passages 9. As shown particularly in Fig. 3, the nozzle partitions have rounded relatively thick inlet ends and relatively thin tapered exit ends.

The foregoing construction is to be taken as 25 typical of any gas turbine construction.

According to my invention, I provide a thin slot 10 at or near the central portion or pitch line of each nozzle partition extending from its exit edge upstream for a short distance and 30 transverse from the front to the back of the partition. For example, a distance of the order of 10 to 15 per cent of the chord of the partition. By a thin slot, I mean a slot having a width of the order of 10 to 20 mils. For example, but not 35 by way of limitation, I have found in the case of a nozzle partition having a chord of 4 inches, a slot 0.5 inch long and 0.1 inch wide to be satisfactory. Preferably, I form each slot 10 approximately at the pitch line that is near the radial center of the nozzle partition for the reason that 40 this gives the shortest non-slotted length of edge.

A central slot is preferable to two slots, one at each edge, because the central slot leaves the edge supported against vibration by the end walls, 45 rather than being cut free.

I have found that by providing such a slot 10 in each nozzle at or near to the pitch line, I overcome the difficulties above pointed out, the slot serving to provide sufficient space for expansion and contraction and serving to reduce the radial-strain set up in the nozzle edge such as 50 would cause the formation of a crack.

My invention is of particular importance to 55 nozzle partitions but in many instances it may be advantageously applied to bucket blades hav-

ing partition or blade members with thin edge portions held between an inner ring or disk and an outer ring or shroud. Broadly, my invention applies to arrangements forming fluid passageways which have a partition or blade secured at its ends between inner and outer rings or walls and having a cross section tapering into a relatively thin edge portion. By providing an intermediate part of such edge portion with a transverse slot extending from the front to the back of the blade member the tendency of cracking or warping of the edge portion is materially reduced.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States is:

1. In a gas turbine for operation at high temperatures, a nozzle structure comprising outer and inner rings between which are nozzle partitions united thereto and defining nozzle passages, said nozzle partitions having thin exit edges and each

exit edge being provided with a transverse slot which extends from the exit edge upstream as regards the flow of gases through the nozzles.

2. In a gas turbine for operation at high temperatures, a nozzle structure comprising outer and inner rings between which are nozzle partitions united thereto and defining nozzle passages, said nozzle partitions having thin exit edges and each exit edge being provided at its pitch line with a transverse slot which extends from the exit edge upstream as regards the flow of gases through the nozzles.

3. A nozzle partition for a gas turbine for operation at high temperatures having a thin exit edge provided with a transverse slot which extends inwardly from such edge.

4. A nozzle partition for a gas turbine for operation at high temperatures having a thin exit edge provided at its pitch line with a transverse slot which extends inwardly from such edge.

5. In a rotary engine subject to high temperatures during operation, an inner and an outer wall, and a blade member having end portions rigidly secured to the walls, said blade having an edge portion of a thickness decreasing toward its edge and a slot extending transversely through an intermediate part of such edge portion.

ALAN HOWARD.
